UNITED STATES PATENT OFFICE

WILLIAM G. KEITH AND JOSEPH A. MANARIK, OF CHICAGO, ILLINOIS, ASSIGNEES TO
WELSBACH TRAFFIC SIGNAL COMPANY, OF PHILADELPHIA, PENNSYLVANIA, A
CORPORATION OF DELAWARE

DESIGN FOR A BULKHEAD SIGNAL

Application filed February 19, 1932. Serial No. 42,940. Term of patent 14 years.

To all whom it may concern:

Be it known that we, WILLIAM G. KEITH, and JOSEPH A. MANARIK, citizens of the United States, both residing at Chicago, in the county of Cook and State of Illinois, have invented a new, original, and ornamental Design for a Bulkhead Signal, of which the following is a specification, reference being had to the accompanying drawing, forming a part thereof.

Figure 1 is a front elevational view of a bulkhead signal embodying our new design, comprising a base portion having a rear wall for supporting a pair of signal lamps, the

base portion converging gently from the rear wall to the forward end and forming a central portion on each side thereof to the supporting surface; and

Fig. 2 is a side elevational view of Figure 1, the support for holding the signal lamp in each instance being duplications of each other.

We claim:

The ornamental design for a bulkhead signal substantially as shown and described.

WILLIAM G. KEITH.
JOSEPH A. MANARIK.
